SAMUEL P. HULL, OF YONKERS, NEW YORK.

ADJUSTABLE SOCKET-BEARING.

1,326,268.

Specification of Letters Patent.

Patented Dec. 30, 1919.

Application filed September 24, 1917. Serial No. 192,847.

To all whom it may concern:

Be it known that I, SAMUEL P. HULL, a citizen of the United States, and resident of Yonkers, in the county of Westchester and State of New York have invented certain new and useful Improvements in Adjustable Socket-Bearings, of which the following is a specification.

This invention relates to socket bearings and has for an object a novel means of adjusting a bearing of this character to take up lost motion resulting from wear; another object is to insure freedom and guard against binding of the bearing.

Referring to the accompanying drawings illustrating one form of my invention; Figure 1, shows an application to the bearing of a rod operating a detector for a railway switch point where a close adjustment is necessary; Fig. 2, shows a detail plan view of its application; Fig. 3 is a side elevation of part of Fig. 2, Fig. 4 shows a modification in its application. Figs. 5, 6, 7 and 8 show different views of the adjusting member and Fig. 9 is an enlarged end view of Fig. 2 with the nut removed.

The part 13, commonly known as a point lug, is bolted to the switch rail 12 and extends beyond the point thereof where it is formed into a rounded extension or tang 31, threaded at the end as shown. This tang forms the socket of the bearing in which the cylindrical eye 36, (shown in section in Fig. 2) of the operating rod 14 is inserted. This rod, by means of the screw jaw 15, moves the circuit controller 16, pivoted at 17. At the end of this circuit controller are two insulated contact plates 18 and 20. When in the position shown, contact plate 18 closes the circuit at contacts 19, thus establishing the circuit of the signaling device 22 from battery 23, through wires 24 and 25. When the switch point 12 is in the other position, contacts 21 and insulated plate 20 may be used to operate a similar circuit, circuit controller 16 then being in the position indicated by the dotted line.

The adjustment of this arrangement requires that a very slight movement of the switch rail 12 from the stock rail 11 should operate the circuit of the signaling device 22 thus detecting a dangerous condition.

It has been found that with this construction there is considerable wear in the

bearing due to vibration incident to its ordinary conditions of service and to the frequency of switch movements. It is the purpose of the present invention to provide a simple and ready means of adjusting the 60 socket bearing so as to take up lost motion due to wear of the bearing surfaces and thus prevent false movements of the circuit controller and, at the same time, provide a bearing that shall work with the greatest freedom, without binding. This is secured by means of the adjusting member, or filler, shown enlarged in Figs. 5 to 8.

This filler, 35, consists as shown of a cylindrical shell having a circular groove 41 less than a semi-circle and of a diameter to fit the tang 31 of the lug 13. Two fillers are placed opposite as shown in Fig. 2 and held in place by being inserted into the eye 36 of operating rod 14. The outer diameter 70 of these fillers or shells is increased at the middle part as shown at 42, forming a convex surface. This convex surface, it will be observed, forms the perimeter of a sphere 80 or ball and when inserted in the eye forms a ball and socket joint. It will be noted that the switch point moves horizontally and describes the arc of a circle and the ball and socket joint prevents binding of the bearing under this movement. It is desirable however, that the operating rod should be rigid in the vertical plane and this I secure by means of the raised edges 45 of the fillers. It will be noted that on the longitudinal edges the diameter of the filler is increased 85 to equal the diameter of the convex surface and when in place as shown in Fig. 9, these raised edges 45 are in a vertical plane within the cylindrical eye 36, thus restricting the ball and socket movement in this direction. 90

The inner end of these fillers is formed into a half hexagon shoulder with the vertical side 44 elongated, and the inner side 43 formed on an inclined plane. This is assembled as shown in Fig. 2, from which it 100 will be noted that the inclined planes 43 engage the shoulder 33 of the lug 13. This shoulder prevents the fillers from turning and from dropping out of place; and when the adjusting nut 32 is tightened the fillers 105 are forced apart on the shoulder 33, thus taking up lost motion in the bearing by the simple operation of tightening the nut.

The shoulders 33 are, preferably, made square as shown in Figs. 2 and 3 although 110

this is not an essential to the use of my invention. In Fig. 4, for instance, the tang 31 is off-centered and the lug 13 does not have squared shoulders. In this case I provide an adapter 37, which is simply a section of tubing fitted onto the tang 31 and provided with tapering sides 38 to engage the inclined planes 43 with the same effect as the shoulder 33. It will thus be observed that the application of my invention simply requires that the cross-section of the end of the tang be so shaped that the fillers are forced apart when the inclines 43 are moved over this cross-section.

15 I wish it to be understood that my invention is not limited to switch points but is generic to socket bearings for any purpose whatever.

Having thus described my invention, I 20 claim:

1. In a socket bearing free to turn, a tang, a support for said tang of different cross-section from said tang, a plurality of fillers, an eye, said eye inclosing said fillers and said tang, and means for forcing said fillers apart.

2. In a socket bearing free to turn, a tang with an adjusting nut, a support for said tang of different cross-section from said tang, an eye, a plurality of fillers split on their longitudinal axis, said eye inclosing said fillers and said tang, and means for taking up lost motion in said bearing by said adjusting nut.

3. In a socket bearing, a tang, a plurality of longitudinal fillers having convex bearing surfaces, an eye, said eye inclosing said fillers and said tang, and means for adjusting said bearing by the position of said fillers on said tang.

4. In combination, a tang of different cross-section at one end, an eye, a plurality of fillers, said fillers having inclined planes

at the ends and convex bearing surfaces, said fillers and said tang inserted within said eye. 45

5. In a socket bearing, a circular member, a support for said member of different cross-section, an eye, a plurality of longitudinal fillers having inclined planes at the end, said circular member and said fillers inserted 50 within said eye, and means for adjusting said bearing by moving said fillers on said circular member.

6. In a socket bearing, a circular member of different cross-section at one end, an eye, 55 a plurality of semi-circular fillers, said fillers having convex bearing surfaces and a hexagon shoulder at one end, said shoulder tapering inward forming an inclined plane, said circular member and said filler inserted 60 within said eye, and means for adjusting said bearing by moving said fillers onto the different cross-section of said circular member.

7. In a socket bearing, a tang, a cylindrical eye, a filler, said filler having a spherical bearing surface and a raised longitudinal ridge, said tang and said filler inserted 65 within said eye to form a ball and socket bearing, said bearing restricted in its movement in one plane.

8. In combination, a cylindrical eye, a circular member, a plurality of semi-circular fillers, said fillers having a spherical convex surface and raised longitudinal edges with 75 a diameter equal to said spherical surface, said fillers and said circular member inserted within said eye and free to move therein.

Signed at New York, in the county of New York and State of New York, this 18th 80 day of September, A. D. 1917.

SAMUEL P. HULL.
